W. L. JENKINS

MEMORANDUM APPLIANCE

Filed Oct. 27, 1926

FIG. 1.

FIG. 3.

FIG. 2.

WILLIAM LIONEL JENKINS, *Inventor*
By Paulin & Paulin, *Attorneys*

Patented May 17, 1927.

1,629,459

UNITED STATES PATENT OFFICE.

WILLIAM LIONEL JENKINS, OF LONDON, ENGLAND.

MEMORANDUM APPLIANCE.

Application filed October 27, 1926, Serial No. 144,480, and in Great Britain November 2, 1925.

This invention relates to apparatus for use in recording engagements and other memoranda of the type comprising a hollow casing or frame wherein a pair of parallel 5 rollers are rotatably mounted and a band of paper is wound from off one roller on to the other passing between apertures in a plate, the apertures being suitably labelled and provided for enabling a pencil or other 10 record to be made on the paper.

The object of my invention is to provide improved apparatus of this type.

Apparatus made in accordance with my present invention is characterized by detachable winding rollers each comprising two longitudinal pieces with coned ends said longitudinal pieces being held together and positioned by cup-shaped sockets, one of said 15 sockets for each roller being mounted on the casing and the other on an axially-movable spring-pressed winding spindle positioned in and passing through the casing.

The invention will be more readily understood by referring to the accompanying 20 drawings in which:—

Fig. 1 shows in perspective one form of appliance made in accordance with this invention;

Fig. 2 shows a detailed view of the inner 25 construction thereof;

Fig. 3 is a plan of Fig. 1.

In the form of apparatus shown, I provide a box or cabinet *a* in which are mounted 30 two winding rollers *b* and *c*. Between these rollers is wound a strip of paper *f* suitably ruled. At each end of one face of the cabinet is a slot *g* in which is disposed an idle roller, and the strip of paper *f*, in 35 passing between the winding rollers *b* and *c* passes through and over these slots *g* and idle rollers *h*, and, in this manner a portion 40 of the paper always lies flat on one face of the cabinet, which permits notes to be made thereon.

On the strip of paper may be printed 45 lines, divisions or any suitable configurations by which memoranda may be classified.

The winding rollers are preferably 50 detachable from the sides of the cabinet and the spindles are made in two sections *i* and *j* between which the ends of the paper strip may be gripped. Each spindle is held in 55 position and the parts thereof are held together by virtue of their ends being tapered and fitting into cup-shaped ends of side

shafts *k m* which are mounted in the sides of the cabinet. Of these side shafts one, *k*, is mounted in bearings in any customary manner and the other *m* forms the winding 60 spindle and is mounted in such a manner that it is capable of axial movement and passes out through the side of the cabinet being provided with a knob or handle *n* by which it may be turned. Discs *o* are 65 mounted on the ends of each side shaft for maintaining in alignment the rolls of paper and a spring *q* is interposed between each disc of each slidably mounted shaft *m* and the side of the cabinet. Stops are moreover 70 provided on the shaft for limiting its axial movement. A projection *r* is also provided on the spindle which projection engages with a slot *p* in the winding spindle and interlocks the two.

A slotted collar *t* is mounted externally of the cabinet through which the shaft passes and an internal groove *u* is formed therein in order that a projection *v* formed on the 75 shaft may not prevent the rotation thereof. The projection however, may pass up the slot *w* in the collar *t* if the shaft is pulled against the spring, and if the shaft be partially rotated it will engage with the top of the collar and hold the shaft in this position, thus holding the spring in compression and allowing the winding spindle to be inserted.

In use it will be seen that engagements or other memoranda may be written on or 80 read from the exposed portion of the paper and if necessary the handles or knobs *n* on the winding shafts may be operated, thus bringing any other desired portion of the paper into view.

In a convenient form of marking the 85 paper the strip is divided up into equal portions, each portion denoting a week in the year, and being sub-divided into days, space being left for the required memoranda.

A grid or plate *z* of any suitable material 90 may be provided, adapted to lie flat over a portion of the exposed writing material *f*, and this plate may bear any words, representations or denominations which would otherwise be written directly on the writing material.

I am aware that roller spindles in two 95 sections held together by end sockets are known in the construction of blinds, screens and the like, and make no claim to such construction, per se.

Detail construction of such apparatus may be varied without departing from the scope of the invention.

What I claim and desire to secure by Letters Patent is:—

1. A memorandum appliance comprising a casing, a pair of winding rollers rotatably mounted in the casing, a band of paper adapted to be wound from one roller on 10 to the other, idle rollers rotatably mounted in said casing over which the band of paper passes and is guided thereby part of the band being exposed and lying flat on the face of the casing, the said winding rollers 15 being of a spindle-like form made in two longitudinal pieces between which the ends of the band of paper is held, the ends of the said two longitudinal pieces being ta-

pered and located and held together by cup-shaped sockets, one of said sockets for each 20 roller being mounted on the casing and the other on an axially-movable spring-pressed winding spindle positioned in and passing through the casing.

2. In a memorandum appliance of the 25 kind described detachable winding rollers each comprising two longitudinal pieces with coned ends, said longitudinal pieces being held together and positioned by cup-shaped sockets, one of said sockets for each roller 30 being mounted on the casing and the other on an axially-movable spring-pressed winding spindle positioned in and passing through the casing.

In testimony whereof, I affix my signature.

WILLIAM LIONEL JENKINS.
